[57] CLAIM

The ornamental design for a dual hardness handle for snow tools, as shown.

DESCRIPTION

FIG. 1 is a perspective view of a dual hardness handle for snow tools showing our new design;

FIG. 2 is a front view thereof;

FIG. 3 is a left side view thereof, the right side view being a mirror image and symmetrical thereto;

FIG. 4 is a back view thereof;

FIG. 5 is a bottom view thereof; and,

FIG. 6 is a top view thereof.

The broken lines showing a blade are for illustrative purposes only and form no part of the claimed design.

1 Claim, 3 Drawing Sheets

FIG. 1

FIG. 2

FIG. 3
